RANSOM W. GREEN, OF BRADFORD, PENNSYLVANIA.

Letters Patent No. 84,351, dated November 24, 1868.

IMPROVEMENT IN COMBINED HAMMER AND NAIL-HOLDER.

The Schedule referred to in these Letters Patent and making part of the same.

To all whom it may concern :

Be it known that I, RANSOM W. GREEN, of Bradford, in the county of McKean, and State of Pennsylvania, have invented a new and improved Combined Hammer and Nail-Holder; and I do hereby declare that the following is a full, clear, and exact description thereof, which will enable those skilled in the art to make and use the same, reference being had to the accompanying drawings, forming part of this specification.

This invention relates to improvements in combined hammers and nail-holders, the object of which is to provide a more convenient nail-holding device.

It consists of the arrangement on the handle, near the hammer, of a fixed and a sliding clamping-jaw, the latter being provided with a spring, for causing it to clamp the nail, and a thumb-piece for retracting it.

It is connected to the handle by a bent strip of sheet-metal, wherein it slides back and forth, for clamping or releasing the nail.

The drawing represents a side view of a hammer having my improved nail-holding clamp combined therewith.

A represents the fixed jaw of the clamp, having an elongated shank, B, by which it is secured to the handle, and which serves as a slide for the movable jaw C, which also has an elongated shank, arranged to

slide on the shank B, within a case of sheet-metal, D, bent around both shanks of the jaws, and secured to the handle, as represented in the drawing, by tacks or screws.

The shank of the jaw C is provided with a thumb-piece, E, by which it may be retracted by the fore finger of the hand in which the handle is held.

It is also provided with a spring, F, for forcing it back, and holding it against the nail.

In some cases, I propose to form the end of the shank into a bow-spring, as represented in red, and secure the end of the latter to the handle.

By this arrangement, the spring serves as the thumb-piece for the shank of the jaw C.

Having thus described my invention,

I claim as new, and desire to secure by Letters Patent—

The jaws A and C, secured to the hammer-handle by the plate D, constructed and arranged to operate as and for the purpose set forth.

The above specification of my invention signed by me, this 22d day of August, 1868.

R. W. GREEN.
